(57) **CLAIM**

The ornamental design for a gasket, as shown and described.

DESCRIPTION

FIG. 1 is a front perspective view of a gasket according to the present invention.

FIG. 2 is a front view of the gasket.

FIG. 3 is a rear view of the gasket.

FIG. 4 is a left side view of the gasket.

FIG. 5 is a right side view of the gasket.

FIG. 6 is a bottom view of the gasket; and,

FIG. 7 is a top view of the gasket.

The dashed broken lines depict portions of the gasket that form no part of the claim.
